UNITED STATES PATENT OFFICE.

ROSS D. BURHANS, OF KEOKUK, IOWA.

ACCOUNT-KEEPING DEVICE.

No. 875,774.

Specification of Letters Patent.

Patented Jan. 7, 1908.

Application filed May 4, 1906. Serial No. 315,164.

To all whom it may concern:

Be it known that I, Ross D. BURHANS, a citizen of the United States, residing at Keokuk, in the county of Lee, State of Iowa, have 5 invented certain new and useful Improvements in Account-Keeping Devices, of which the following is a specification.

This invention relates to means for keeping accounts and it has for an object to provide an improved means by which the ordinary pass-book may be dispensed with and a duplicate record made by merely one entry, one record to be given to the customer and the other to be retained by the dealer.

15 A further object is to provide a means by which the exact total of any account may be ascertained either by the customer or by the dealer, at a moment's notice without adding columns of figures.

20 Other and further objects will appear in the following description and will be more particularly pointed out in the appended claims.

In the drawings, Figure 1 is a front elevation of a cabinet for retaining the different accounts. Fig. 2 is a vertical section through one of the sections of the cabinet. Fig. 3 is a perspective view of one of the receptacles. Fig. 4 is a top plan view of one of 25 the receptacles. Fig. 5 is an inside view of the cover showing it covered with a carbon paint. Fig. 6 is a vertical section of one of the receptacles. Fig. 7 is a top plan view of one embodiment of the strips. Fig. 8 is a 30 detail view of the inside case, showing the means for holding the labels in place.

The means involves the use of a number of receptacles equal to the number of accounts to be kept. These receptacles may be arranged in any suitable manner but I prefer to arrange them in a cabinet. The cabinet shown, comprises a pair of uprights 1 supported and secured, if desired, to any suitable base 2, such as a counter. These uprights are provided on their opposed faces with horizontally alined ribs 3. A number of cabinet sections 4 provided with grooves in their ends, is then fitted between the uprights by a sliding movement. By making 45 the cabinet in sections, it is thus possible for the dealer to purchase a system sufficient for his business only and to increase the size of his system as the business grows. Each section is divided into a number of compartments, each approximately equal in size to the size of the receptacles, the walls or parti-

tions of the compartments being formed of sheet metal to reduce the size of the cabinet. The receptacles should be alphabetically arranged within the cabinet. Each receptacle 60 consists of an outer case 5 and an inner case 6. The outer case is of rectangular form open at 7 at its front end, has its sides cut away at 8 to permit the easy removal of the inner case, and has a cover 9 hinged at 9^a to its rear end. 65 This cover 9 is of a length slightly in excess of the body of the receptacle so that there is formed a projection 10 by which the receptacle may be removed from the cabinet. On its outer faces, the cover is provided with 70 paper clips 11 and 12, the clips 11 holding one end of a tablet of forms 13 and the clips 12 holding the other end of said tablet. The purpose and the form of this tablet will be hereinafter described. Upon the inside, the 75 cover is provided with two transverse depressions 14 in which are fitted elastic bands 15 which hold a carbon sheet 16 at both ends to the cover, or in place of the carbon sheet 16, a carbon surface 17 as shown in Fig. 5 may be 80 employed. This latter carbon surface is applied in liquid form whenever the surface makes faint marks. The purpose of the carbon surface 16 or 17 will be hereinafter described.

85 The inner case 6 is open at both ends, its side walls near its front end being provided with inwardly extending fingers 18 while its bottom wall has flexible fingers, the portions 19^a of which serve with the fingers 18 to act as a label holder to hold a card or label 20. The portions 19^b overhang the card and label and project inwardly. The rear end of the inside case is provided with an overhanging finger 21.

90 Within the inner case of each receptacle are fitted two strips A and B which are folded together as shown in Fig. 3. To prevent accidental removal of these strips from the receptacles, overhanging fingers 19 and 21 are provided, which permit said strips to be removed gradually by pulling on the upper ends thereof. One of these strips, as A, acts 95 as a record for the strip B. It may be blank and should preferably, be transparent. The other strip B is divided throughout its length by main or heavy transverse lines 22 into sections and each line is provided with denominational numerals 23 on each side thereof and at each end designating fractional portions of the whole number of divisions on the strip, the numerals at each end of the line

being duplicates of each other. The numerals on one side of the strip start at the first line at one end of the strip with a certain number, that shown being 5 and increase at 5 each succeeding line an amount equal to the number from which they start. The numerals on the opposite edge of the strip start with the same number and from the opposite end of the strip. They also increase in the 10 same manner. It will thus be seen that each line has two different numbers in duplicate at each end. Further, it will be seen that from one end the numbers increase on one side and decrease on the other side of the 15 strip. There is thus formed, an increasing arithmetical series on one edge of the strip, and a decreasing arithmetical series on the other edge. By this means there is provided a strip divided into sections appropriately 20 marked in progressively increasing series. The space between two heavy transverse lines is subdivided by a number of light lines to provide spaces between them equal in 25 number to the number with which the succeeding heavy lines increase. In Fig. 7, I have shown a strip having the numbers arranged along one edge only.

Assuming that a customer is dealing on credit, a receptacle is provided with his name 30 on the label 20. Upon his purchase, the dealer or his clerk removes the upper ends of the strips A and B from the inner case 6 and rests them upon the carbon surface 16 or 17 with the transparent strip beneath the strip 35 B. The date of the purchase together with the articles purchased are then written on the strip B, the carbon surface causing a record to be made on the under surface of the strip A. The matter on the strip A will of 40 course be copied backwards on the back of the strip, but as this strip is transparent, the matter may be read from the other side. After the record is made, the strip B is torn either on a heavy or a light line a distance 45 from one end of the ticket sufficient to include a number of lines equal to the amount of the purchase, the transparent tape A being torn at the same time and the same amount. The torn-off portion of the strip B is given to the 50 customer who may, by referring to the last heavy line ascertain immediately the amount that he owes the dealer. The dealer retains the torn-off portion of the transparent strip A, placing it within the receptacle between 55 the inner case and the outer case. Should the debtor return any of the goods or pay a small amount, credit is given on the tablet 13 upon the top face of the cover. These forms are each provided with an appropriately designated column 24 for the date, with an appropriately designated column 25 for the amount, and with an appropriately designated column for the total credit. When the debtor comes in to settle his account, the 60 dealer refers to the first line of the upper end 65

of the strip B to ascertain the total amount of purchases and then deducts from this the credits on the credit tablet 13, leaving the amount actually due. In this way, no inaccuracies can arise due to the counting of 70 many columns of figures, and the amount due can be ascertained almost immediately, either by the dealer or by the debtor. If an account is settled before a strip B is entirely used, the strips are reversed, that is, they are 75 used from the other end. The strips B may be of any denomination.

Where a dealer gives a certain percentage off for cash purchases, the strips B could be of another color and the receptacles should 80 be made out in the name of the cash buyer. The strip could either be purchased in advance for a reduced price, or redeemed when a complete strip has been used. When so used, the decreasing numbers would indicate 85 to the purchaser, the amount he has to his credit or the amount he has to buy before he could have his strip redeemed.

When employed for keeping an account of the cash sales, the strips may be of still 90 another color. One receptacle could be provided for each clerk, thereby keeping a record of each clerk's sales. The torn-off portion of the strips B would identify the purchaser, should he desire to return the goods, or could 95 be redeemed when the purchase amounted to a certain sum. As a further advertisement, the dealer could stamp or otherwise mark one or more portions of each cash strip, to provide a premium portion, as shown at 100 26, Fig. 7, and redeem the marked portions either singly or in certain combinations of said premium portions. Trade would in this manner be stimulated as no purchaser would know when he would receive a premium, as 105 different portions of the cash ticket would go to different purchasers, but owing to the chance attached to each purchase, more goods would be bought from a dealer employing this system. There could also be a cash 110 sale strip of still another color which would indicate that the goods were sold on a special sale day on which there would be no discount.

It is apparent that the strips A and B may be secured together, either along one of their 115 longitudinal edges or along one of their ends without departing from the spirit of my invention.

Having thus described my invention, what I claim and desire to secure by Letters 120 Patent is:

1. Means for keeping accounts comprising a receptacle having a hinged cover, a carbon surface carried by the inner face of said cover, and a pair of strips located within the receptacle, one of said strips being transparent.

2. Means for keeping accounts, comprising a receptacle having a hinged cover, a carbon surface carried by the inner face of the cover, a blank carried by the outer face of the cover,

- and a pair of strips within said receptacle, one of said strips having marks arranged in an increasing series.
3. Means for keeping accounts, comprising a receptacle having a hinged cover, a carbon surface carried by the inner face of the cover, a blank carried by the outer face of the cover, and a pair of strips within said receptacle, one of said strips having marks thereon arranged in an increasing series, and the other of said strips being transparent.
4. Means for keeping accounts comprising a receptacle having a hinged cover, a carbon surface carried by the inner face of the cover, a blank carried by the outer face of the cover, and a pair of strips within said receptacle, one of said strips being divided into sections having two sets of numbers, one of which increases, and the other of which decreases from one end.
5. A receptacle formed of an inner and an outer case, the outer case open at its front and cut away on its sides, and having a hinged cover carrying a carbon surface and the inner case having flexible fingers at its front and at its rear, and a label at its front end.
6. A receptacle having a hinged cover, and a label holder, a carbon surface carried by the inner face of the cover, and paper clips on the outer face of the cover.
7. A receptacle having a hinged cover, a carbon surface on the inner face of the cover, and flexible fingers overhanging the interior of said receptacle at the front and the rear thereof.
8. A receptacle, formed of an inner and an outer case; a hinged cover carried by the outer case, and a carbon surface on the inner face of the cover.
9. Means for keeping accounts comprising an inner case and an outer case, a pair of folded strips arranged within the inner case, one of said strips being adapted to act as a record for the other, a receptacle formed between the inner and outer cases, and a closure for the outer case.
10. Means for keeping accounts comprising a receptacle, a hinged cover for the receptacle, a carbon surface carried on one face of the cover, and means for securing a blank pad to the other face of the cover.
11. Means for keeping accounts comprising a receptacle provided with a hinged cover carrying paper clips on its outer face and a carbon surface on its inner face.
12. Means for keeping accounts, comprising a receptacle carrying a carbon surface and flexible fingers overhanging the interior of the receptacle at opposite ends thereof, and a folded strip arranged in the receptacle and held by the fingers.
13. A receptacle having a cover hinged to the rear end of the same, projecting beyond the front end, and carrying a carbon surface and a label holder on the front end of the receptacle.
14. Means for keeping accounts comprising an inner case and an outer case, a receptacle formed between the inner and outer cases, a folded strip arranged in the inner case, and a hinged closure for the outer case.
15. Means for keeping accounts comprising a receptacle formed of an outer case having a hinged closure provided with a carbon surface, and an inner case having fingers overhanging its compartment at opposite ends.

The foregoing specification signed at Keokuk Iowa this 10th day of April, 1906.

ROSS D. BURHANS.
